UNITED STATES PATENT OFFICE.

PHILIP JAMES KENT, OF DETROIT, MICHIGAN, ASSIGNOR TO CHRYSLER CORPORATION, OF HIGHLAND PARK, MICHIGAN, A CORPORATION OF DELAWARE.

INSTRUMENT-BOARD PANEL AND LIGHTING CONSTRUCTION.

Application filed July 7, 1924. Serial No. 724,694.

To all whom it may concern:

Be it known that I, PHILIP JAMES KENT, a citizen of the United States, and resident of the city of Detroit, county of Wayne, and 5 State of Michigan, have invented certain new and useful Improvements in Instrument-Board Panels and Lighting Construction, of which the following is a specification, reference being had to the accompanying drawings.

It is the primary object of my invention to provide an instrument board panel wherein in all the instruments are centrally grouped in a removable unit and wherein a lighting 15 construction for the same is provided in such a manner that no direct rays from the light will strike the faces of any of the instruments and so that the light will be diffused so as to equally illuminate all the instrument faces.

It is a still further object of my invention to so construct the instrument board panel that light from the illuminating means contained therein may be diffused downwardly 25 on the outside of the panel, so as to illuminate the floor board of the automobile in which the panel is placed and permit illumination of such things as transmission locks, and the like, usually contained on the 30 floor board, or adjacent parts of the automobile.

With the above and other objects in view, my invention consists in the arrangement, combination and construction of the various 35 parts of my improved device as described in the specification claimed in my claims and shown in the accompanying drawings, in which:

Fig. 1 is a front elevation of my improved construction.

Fig. 2 is a like view with the cover plate of the panel removed.

Fig. 3 is a sectional view taken on line 3-3 of Fig. 2 but with the cover plate in 45 place.

Fig. 4 is a rear elevation of the cover plate.

Fig. 5 is a rear elevation of the panel.

I have shown a casing 5 consisting of a 50 vertical portion of oblong form having a continuous forwardly extending rim. Mounted in the vertical portion, or back of the casing 5, by means of a plurality of screws or bolts 6, extending through ears in the securing plates 8, are a plurality of in-

struments, designated generally as 7; said instruments consisting in this instance of a speedometer, odometer, gasoline tank, heat indicator, oil gauge and ammeter. A plurality of ears 9, having apertures 10 therein, are provided around the edges of the panel 5 for securing it to the instrument board proper.

A cover plate consisting of a securing rim 11, a plate 12, having a plurality of 65 openings 13 therein, and a glass face 14, is secured over the forwardly extending flanges of the casing 5, the glass covering 14 being held in place between the edge 15 of the rim 11 and the plate 12 by means of screws or 70 rivets 16, extending through the edges of the plate 12 and the rim 11.

The plate 12 is provided with a pair of rearwardly extending flanges or shields 17, shaped to conform with the formation of 75 the two upper central instruments shown. A shield 18 extends forwardly from the casing 5.

Extending into the casing 5 and mounted in the rearward projection 19 thereon is an 80 electric bulb 20, which may be connected through the wiring 21 to a suitable source of electric current such as a storage battery.

The plate 12 is so positioned as to provide only a small clearance between it and the 85 faces 22 of the various instruments and the openings 13 in the plate 12 are so positioned that the various faces of the instruments may be read therethrough.

The instruments are so shaped and positioned in the casing that a suitable space is provided between the openings in plate 12 for placing the name, trade-mark or emblem 23 of the maker thereon to produce an 90 ornamental effect.

The shields 17 and 18 positioned as they are around the light bulb 20 and the adjacent instrument faces, prevent direct rays of light from the bulb being directed over the instrument faces and cause the light to 100 be diffused upwardly (although a small portion thereof will pass downwardly between the shields) so that it will spread through the casing and give an illumination of substantially equal brightness to all of the instrument faces. This illumination consists of a soft, even glow which has no glare.

Directly over the light bulb, or other source of illumination 20, is provided a frame 24, secured to the casing 5 by means 110

of screws 25. In this frame is disposed a small piece of glass, or other transparent material 26, thus permitting a certain amount of light from the bulb, or other source of illumination 20, to escape from the casing 5 therethrough.

Secured to the top of the forwardly extending rim of the casing 5, directly above the frame 25, by means of screws 27, is a small downwardly curved deflecting plate 28, which will cause the light rays passing through the glass or shield 26, to be deflected downwardly so as to illuminate the floor board or other desired portions outside of casing 5, where such illumination is desired. By reason of this deflection, this additional light will likewise be indirect so as to not blind the driver or produce an undesirable effect.

20 I have found it desirable to paint the metal, or other substances used in the shields and casing, against which the light rays will be directed, in white, so as to make of them better reflecting surfaces.

25 It is obvious that various changes may be made in the arrangement, combination and construction of the various parts of my improved device without departing from the spirit of my invention, and it is my intention to cover by my claims such changes as may be reasonably included within the scope thereof.

What I claim is,

1. A device of the character described, comprising a casing, a plurality of instruments therein, a source of illumination in said casing, said source being positioned

rearwardly of the instrument faces, an aperture plate over said instrument faces, and shields so positioned as to co-operate with said plate to deflect direct rays of light from the faces of said instruments and at the same time diffuse sufficient light to illuminate them.

2. A device of the class described, comprising a casing, a plurality of instruments therein, a source of illumination disposed between two of said instruments and below the top of the same, shields disposed between said instruments and said source, adapted to deflect direct light rays from said source and means permitting light from said source to be diffused indirectly over the faces of said instruments.

3. A device of the class described, comprising a casing, a plurality of instruments therein, a source of illumination in said casing, a cover plate for said casing through which the faces of said instruments may be seen, shields on said cover plate extending rearwardly therefrom adapted to at least partially deflect direct light rays from said source of illumination away from the faces of said instruments.

4. A device as characterized in claim 2, wherein an opening is provided in said casing adjacent said source of illumination, whereby light may pass through the same out of said casing, and a deflecting shield positioned in the path of such light adapted to deflect indirect rays to a desired point outside said casing.

PHILIP JAMES KENT.
